DESIGN FOR A MOTION PICTURE PROJECTOR

David Pelton Moore, Avon Park, Fla., assignor to W-R-M, Inc., a corporation of Delaware

Application November 21, 1933. Serial No. 49,811

Term of patent 14 years

To all whom it may concern:

Be it known that I, DAVID PELTON MOORE, a citizen of the United States, residing at Avon Park, in the county of Highlands and State of Florida, have invented a new, original, and ornamental Design for Motion Picture Projectors, of which the following is a specification, reference being had to the accompanying drawing, forming part thereof.

Figure 1 is a front perspective view of a motion picture projector, showing my new design, and Figure 2 is a similar view thereof taken from the rear.

I claim:—

The ornamental design for a motion picture projector, as shown.

DAVID PELTON MOORE.
